Des. 412

Charles Feuner, of Cincinnati, Ohio,
assignor to
M. Greenwood & Co.
Letters Patent No 412, dated, Sept. 9th 1857.

The schedule referred to in these Letters Patent
and making part of the same.

To all whom it may concern:

Be it known that I, Charles Feuner, of the city of Cincinnati, in the county of Hamilton and state of Ohio, have invented or produced a new & original design for a stand for shovels and tongs, and I do hereby declare that the following is a full and exact description of the same, reference being had to the accompanying drawings.

The shell or dish, which forms the base on which the shovel & tongs are to rest, and which also serves as a receptacle for dirt or ashes from the shovel and tongs, represents a ribbed shell, the ribs are alternately flat and concave.

The concave ribs are ornamented, Figure II, with a row of pearls, decreasing in size from the front towards the back part of the dish, the back part of the dish or shell is ornamented with leaf-work as shown in Figure II, one large leaf running towards the middle of the dish and having a smaller leaf on either side, inclining to the

sides or edges of the dish, the middle or large leaf extending back to the foot as shown in Figure II, — the feet which may be three or more in number, and on which the base or dish stands are each composed of two scrolls, intersected by a bead — on the back part of the dish, at the stem end of the small leaves the standard or upright is placed, the lower part of which, as seen in Figure I, represents two Dolphins, with their tails twined together forming a knot.

The heads, in which a bolt is inserted for the purpose of fastening the standard to the dish, by a screw & nut or otherwise, rests on the raised ends of the two small leaves, the upper part of the standard as seen in figure I, is a fluted stem or column, ornamented where it rises from the Dolphins, with two bunches of differently shaped leaves, intersected by a bead and is also ornamented at the top with leaves & beads, below where the Foot, and Handle, are affixed to it.

The Foot as represented in Figure III, are composed of two scrolls extending in opposite directions from some small leaf work by which they are connected together and attached to the standard.

The Handle is formed of two vines running out of a cluster of leaves, crossing each other & having the ends twisted together in a pendant position in the centre, and ornamented with leaves & a cluster of grapes, and are connected together at the top by an acorn, the shape and ornamenting of the handle are fully shown in the drawing, Figure I, which also shows and represents the stand, complete in a perspective front view.

What I claim as my invention and desire to secure by Letters Patent is the design & configuration of the stand as a whole, as fully shown & represented in the

Des. 4/2

drawing at Figures I. I claim also the particular ornamenting of the shell or dish used as a base, and the configuration and ornamenting of the standard or upright and the design of the Hooks, and the handle as fully shown and represented in the Drawings at Figures I, II & III, and herein before fully set forth.
